UNITED STATES PATENT OFFICE.

WILLIAM HUCK, OF NEW YORK, N. Y., ASSIGNOR TO R. HOE & CO. INC., OF NEW YORK, N. Y., A CORPORATION OF NEW YORK.

MECHANICAL MOVEMENT FOR MOLDING PRESSES.

Application filed May 15, 1926. Serial No. 109,216.

My invention relates to mechanical movements for molding presses; and its objects are to impart at intervals a fast and slow motion to the platen, to exert great pressure between the matrix and the form after a brief interval of lesser pressure, to mold more effectively the matrix, to utilize a system of changing leverages, and in general to simplify and render more efficient the construction and operation of the several parts.

In molding matrices for printing plates, it is necessary that every part of the face of the type of the form should be perfectly impressed into the sheet from which the matrix is formed. To secure this result effectively, I first employ mechanism which swiftly brings the type into contact with the matrix after which the pressure between the two is greatly increased through changing leverages more slowly operated by auxiliary mechanism. Through the first step the press-head carrying the platen is lowered rapidly until the same rests upon and through the action of gravity presses down upon the form, and through the second step by the use of considerably greater pressure every portion of the type contacting with the matrix is forced therein and a perfect and complete impression is thereby produced. Thus, my improved matrix molding press employs mechanical movements which impart a fast and slow motion to the platen. In pressing the matrix into the form, the fast motion operates until the weight is supported on the form, at which time the slow motion is actuated, thereby greatly increasing such pressure through the leverages used by me.

Attention is hereby directed to the accompanying drawing in which similar numerals of designation refer to similar parts throughout the several views. Figure 1 represents a longitudinal section of my improved apparatus, showing the relative positions of the various parts of the operating mechanism at the time when the press-head has been raised to its highest extent; Fig. 2 is an end view of my apparatus partly in section, showing the relative positions of the various parts at the time when the press-head has been lowered to a position where it rests upon the matrix sheet; Fig. 3 is an end view similar to Fig. 2 showing the relative positions of the various parts when further action will complete the impress

upon the matrix sheet. Lines C—C of Fig. 4 and D—D of Fig. 5 show the plane of this view; Fig. 4 is a horizontal section on line A—A of Fig. 1, looking in the direction of the arrow; Fig. 5 is a longitudinal section taken on line B—B of Fig. 1, looking in the direction of the arrow.

Referring to the drawing, the motor 1 is connected by sprocket chain 2 to the sprocket 3 which is mounted on shaft 25 journaled in bearings 26 secured to the main frame 27. The shaft 25 carries the worm 4 which meshes with worm gear 5 mounted upon shaft 6, which is journaled in bearings 28 secured to the main frame 27. Shaft 6 at the lower portion thereof is provided with a screw thread 29 which engages with the threaded opening of the nut 7. This nut 7 is connected by links 8 (see Figs. 3 and 4) to the levers 9. Integral with the levers 9 is the shaft 10 which carries eccentric portions 11 (see Figs. 4 and 5), which are preferably offset in substantially a horizontal direction. The shaft 10 is journaled in bearings 23 carried by the yoke 22. Straps 12 engaging with said eccentric portions 11 are connected to the thrust member 13 which engages a recess in the main frame of the machine indicated at 14. The thrust member 13 is connected by link 15 with bell crank lever 16, which is pivoted to the main frame at 33. The yoke 22 is connected by means of straps 21 to the pressure head 30 carrying the platen 20. The bed 19 is integral with the frame of the machine carrying the form 31, upon which is placed the matrix 32. Levers 9 cooperate with the fulcrum 17 and pin 18 in the manner hereinafter to be described. The straps 21 are constructed to move vertically between guides 33 of the main frame. The pin 18 is mounted to move freely in a vertical direction in an opening in bracket 34 secured to the main frame. The lower portion of said pin 18 is normally in contact with the short arm of the lever 16.

To operate my apparatus the motor 1 is started and through the movement of connecting mechanism the nut 7 is caused to travel up or down the screw threads 29, depending upon the direction of rotation of the motor. When the press-head 30 carrying the platen 20 is at its highest position as shown in Fig. 1, the ends of the levers 9 rest upon the fulcrum 17 and the nut is in the uppermost position of its travel. The nut 7

through the operation of the motor and connecting mechanism is then caused to travel downwardly on the screw threads 29, the shaft 10 being lowered at a speed approximately one half of the speed of the nut 7, as the leverage is about two to one. The platen 20 descends at the same speed as the shaft 10 until the platen rests upon the form placed under it as shown in Fig. 2.

10 Thereafter further downward movement of the nut 7 will rotate the shaft 10, causing the opposite ends of the levers 9 to leave the fulcrum 17 and to assume the position shown in Fig. 3. In the meantime pressure is removed from the pin 18 and the spring 24 acts to move lever 16, and by means of link 15 thrust member 13 is pushed into the recess 14 of the main frame. Continued movement of the nut 7 downwardly and further rotation of the shaft 10, acting through the eccentric portions 11, causes a pressure to be exerted between the thrust member 13 and the adjacent portion of the main frame which is communicated to the platen, causing it to be drawn with considerable force down against the matrix and form resting upon the bed 19. Under these conditions, the mechanical action is such that the press is operated through a lever motion 20 with a fulcrum at the point F, the power or drive being at point P and the weight at point W. WP is therefore the long arm of the lever and FW the short arm. It is understood that the thrust from point F is 30 direct to point 14 which is fixed, and from point W through yoke 22 and straps 21 to the platen 20.

It will thus be seen in pressing a matrix the platen 20 is lowered rapidly until it 40 rests on the type form, and that thereafter the motion is very much slower with a correspondingly increased leverage, permitting a motor of moderate size to exert a very heavy pressure.

45 To raise the platen 20, point P of the levers 9 is raised, thereby causing the shaft 10 to rotate and simultaneously relieving the pressure between the thrust member 13 and the adjacent frame at the recess 14. The opposite end of the lever is depressed until it strikes the fulcrum 17; pin 18 is depressed, thereby operating lever 16 and link 15 and moving thrust member 13 out of engagement with the recess 14, as shown in Fig. 2. 50 Further upward movement of the point P results in a faster motion of platen 20 by a change in the leverage. 17 now becomes the fulcrum of the lever with the distance between 17 and P, constituting the long arm, and the distance from 17 to W the short arm. The platen is then returned to the position shown in Fig. 1.

In addition to using the particular form of press, herein described, for making matrices, my invention could also be used for

making molds for electrotypes. So, also, it could be used for molding plastic material in sheet form, as by embossing the same. It might also be possible to utilize my improved press where the material for the work is in powdered form, similar to that used for the bakelite products.

While I have shown a preferred and particular application of my invention in the apparatus described and set forth herein, I 75 by no means desire to limit my invention to the precise mechanisms shown, since, as is obvious, various changes and modifications might be made therein without departing from the spirit or purpose of my invention. 80

What I claim and desire to secure by Letters Patent is:

1. In a molding press, the combination of a stationary bed, a movable platen mounted thereon, a lever provided with changing fulcrums operatively connected to said platen, and mechanism for automatically bringing said platen into contact with said bed with varying pressure produced by said changing fulcrums.

2. In a molding press, the combination of a stationary bed, a movable platen mounted thereon, and single lever mechanism successively engaging with two fulcrums, and operating to bring said platen into contact with said bed, the first fulcrum operating automatically to produce quick action with relatively light pressure, and the second fulcrum operating automatically to produce relatively slow motion with proportionately heavy pressure.

3. In a molding press, the combination of a stationary bed, a movable platen mounted thereon, a rocking lever operatively connected with said platen and provided with two fulcrums, one of which causes said lever to move quickly with relatively light pressure and the other of which causes said lever to move slowly with proportionately heavy pressure, and automatic mechanism for successively operating the same.

4. In a molding press, a stationary frame carrying a form, a movable press-head and platen mounted on said frame, a rocking lever carried by said head for depressing and elevating the same to and from said form and provided with two fulcrums, means for successively moving the lever on said fulcrums, and mechanism cooperating therewith to increase the leverage of said lever and the pressure between said platen and form.

5. In a molding press, a stationary frame carrying a form, a movable press-head and platen carried thereon, a sliding yoke secured to said press-head, a shaft journaled to said yoke, a lever provided with two fulcrums mounted upon said shaft and arranged to slide the platen to and from the form, and mechanism for operating said lever successively upon said fulcrums to in-

crease the leverage of the same and the pressure between the platen and form.

6. In a molding press, a stationary frame carrying a form, a movable press-head and platen carried thereon, a sliding yoke secured to said press-head, a shaft journaled to said yoke, a rocking lever provided with two fulcrums mounted upon said yoke and arranged to slide the platen to and from said

form, one fulcrum operating automatically to provide quick action with relatively light pressure, and the other fulcrum operating automatically to produce relatively slow motion and proportionately heavy pressure.

In testimony whereof I have hereunto set my hand this 12th day of May, 1926.

WILLIAM HUCK.
